UNITED STATES PATENT OFFICE

IRVING KULIK, OF BROOKLYN, NEW YORK

RAILWAY RAIL

Application filed September 1, 1927. Serial No. 216,957.

This invention relates to railway rails and has for its object to provide a method and means as well as a rail of which the ends may be fusible.

5 Fig. 1 shows a section of railway rail having on one of its ends and extending over partly on its lateral sides weldable material, which is lower in melting point than the remainder of the rail.

10 Fig. 2 shows the opposite end can, of course, also have weldable material and said weldable material can be secured in a number of ways to the rail but is preferably shown as fused to the rail.

15 Fig. 2 shows two adjoining sections of rail, the weldable material forming the ends of the said rail sections being adjacent each other.

20 Fig. 3 is a bowed rail alignment temporary maintainer.

By placing the rail section 1 adjacent the rail section 2 as shown in Fig. 2 and temporarily fastening them to one another with the maintainer, Fig. 3, and heating the 25 weldable portions 3 and 4 of the rails, Fig. 2, the two rail sections 1 and 2 become permanently fixed to one another.

The welding can be done by an oxy-acetylene torch or by electricity.

30 Prior to the welding, a maintainer, Fig. 3, is attached—one each side of the lateral sides of the adjoining rails. Bolts are passed through holes viz., 7 and 8 of the maintainer and which bolts pass through the holes 5, 35 6 and 9, 10 of the rails. Nuts are then not too tightly applied to the bolts.

With the softening of the weldable ends of the adjoining rail sections force is applied upon the maintainers, Fig. 3, in a direction 40 of arrow R. Thus the face 11 by forcing the face 12 brings about a tight joint between the softened weldable ends 3 and 4 of the rail sections.

Fig. 3 is of a substance having the pliability approximately of wrought iron. The 45 opposite arms of the U like part of Fig. 3 are grasped by the jaws of a mechanism acting like a pair of pliers. By bringing the jaws together simultaneously with the welding process the force applied to the main-

tainer, Fig. 3, not only welds more closely the sections of rail to one another but causes thus, also, the powerful forging of the sections together.

What I claim as new and wish to secure 55 by Letters Patent is:

1. A railway rail having an end portion of a lower melting point than that of the major portion of the rail.

2. A separate railway rail section consisting of metals of different fusibility integrally thereof. 60

3. A separate railway rail section consisting of metals of different fusibility integrally thereof and an end of said rail having a 65 lower melting point than that of the adjacent part of the rail section.
